[57] **CLAIM**

The ornamental design for a light guide for endoscope, as shown and described.

DESCRIPTION

FIG. 1 is a front, top and right side perspective view of a light guide for endoscope, showing our new design; FIG. 2 is a rear, bottom and left side perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof.

The bracketed portion in the several views is 96 cm in length and is omitted for convenience of illustration only.

FIG. 1

FIG. 2

FIG. 3

FIG. 4

FIG. 5

FIG. 6
